ATTORNEY

UNITED STATES PATENT OFFICE

PAUL E. G. JENSEN, OF GRANTWOOD, NEW JERSEY, ASSIGNOR TO RADIO CORPORATION OF AMERICA, A CORPORATION OF DELAWARE

SOUND PICK-UP DEVICE

Application filed August 14, 1931. Serial No. 557,045.

This invention relates to sound pick-up devices such as are used in the production of sound pictures and has for its object the provision of an improved apparatus and method of operation whereby sound may be readily picked up from any desired location.

While the present invention is of particular utility in the production of newsreels, it will be apparent that it is also useful in studios and other locations. Among the novel features involved are a microphone or similar sound pick-up device and a sound concentrator arranged to be adjusted readily to point in any desired direction, means for finding the range of the point at which sound originates, and means for adjusting the sound concentrator with respect to the microphone in accordance with the determined range so that the microphone is located at the 20 focal point of the concentrator.

Among further objects of the invention are the provision of improved means for sighting the microphone and sound concentrator, for finding the range of the point 25 from which the sound originates, for adjusting the concentrator in accordance with the determined range and generally the provision of an improved pick-up device which is readily assembled and may be readily adjusted in a manner to insure proper operation under different conditions encountered in newsreel work.

My invention will be better understood from the following description when considered in connection with the accompanying drawing and its scope will be pointed out in the appended claims.

Referring to the drawing

Fig. 1 is a fragmentary view of the sound pick-up device constructed in accordance with my invention.

Fig. 2 is a similar view taken at a different angle, and

Fig. 3 illustrates the mounting of the 45 range finder device on the sound concentrator.

The pick-up device is similar to prior devices of this character in that it includes a sound concentrator 10, a microphone 11, and 50 a support 12 upon which the concentrator

and microphone are mounted. It differs from prior devices in various details. It will be observed that the support 12 is arranged to cooperate with a bifurcated member 13 provided with a thumb screw 14 for locking 55 it to the support 12 and at its upper end with a shaft 15 upon which the microphone and sound concentrator are supported through members 16 and 17.

Angular adjustment of the sound concentrator and microphone is effected by means of the hand wheel 18. This adjustment is determined by sighting means including an opening or peep hole 19 in the sound concentrator and a sighting member 20 mounted 60 on top of the microphone. Adjustment of the sound concentrator 10, with respect to the microphone 11, is effected by means of a knob 21. This knob is calibrated and the adjustment is made in accordance with the 65 reading indicated by a range finder 22. The range finder may be of any suitable well known form mounted at one edge of the sound concentrator. It will be understood that the support 12 may form part of a tripod 70 or in any other suitable supporting means and that the leads 23 of the microphone are connected to a sound recorder through suitable amplifying means (not shown).

In the operation of the device the hand 80 wheel 18 is adjusted until the sighting means 19 and 20 indicate that the microphone and sound concentrator are properly pointed at the point where the sound originates. By means of the range finder 22 the distance to 85 the point of sound origin is determined and the knob 21 is adjusted accordingly so as to insure that the microphone is located at the focal point of the concentrator. Angular adjustment about the vertical axis of the support is of course effected by loosening the thumb screw 14 and turning the member 13 about the upper end of the support 12.

From the foregoing description it will be evident that the improved device is readily set 90 up and adjusted to operate under a wide variety of conditions.

I claim:

1. A sound pick-up device including a concentrator and a support therefor, a micro- 100

- phone arranged within said concentrator to receive the concentrated sound, means mounted on said support for determining the distance between said device and the point of sound origin, and means for adjusting the spacing between said microphone and said concentrator in accordance with said distance. 70
- PAUL E. G. JENSEN. 75
2. A sound pick-up device including a concentrator and a microphone arranged within said concentrator to receive the concentrated sound, a support for said microphone and concentrator, means mounted on said support for aligning said microphone and concentrator with the point of sound origin, means for determining distance between said device and said point, and means for adjusting the spacing between said microphone and said concentrator in accordance with said distance. 80
3. A sound pick-up device including a concentrator and a microphone arranged within said concentrator to receive the concentrated sound, means including a peep hole in said concentrator and a sighting member mounted on said microphone for aligning said microphone and concentrator with the point of sound origin, means for determining distance between said device and said point, and means for adjusting the spacing between said microphone and said concentrator in accordance with said distance. 85
4. A sound pick-up device including a concentrator, a microphone arranged within said concentrator to receive the concentrated sound, a range finder mounted on said concentrator for determining distance between said device and the point of sound origin, and means operable from the rear of said concentrator for adjusting the spacing between the said microphone and the said concentrator in accordance with said distance. 90
5. A sound pick-up device including a concentrator, a microphone arranged within said concentrator to receive the concentrated sound, means for aligning said microphone and said concentrator with the point of sound origin, and means operable from the rear of said concentrator for adjusting the spacing between said microphone and said concentrator. 95
6. A sound pick-up device including a concentrator, a microphone arranged within said concentrator to receive the concentrated sound, means for aligning said microphone and said concentrator with the point of sound origin, means operable from the rear of said concentrator for adjusting the spacing between said microphone and said concentrator, and means for adjusting said microphone and said concentrator about a vertical axis. 100
7. A sound pick-up device including a concentrator, a microphone arranged within said concentrator to receive the concentrated sound, means mounted in fixed relationship with said microphone and concentrator for 105
